STITCH MARKING DEVICE

Johan E. Larsson, Copenhagen, Denmark, assignor to United Shoe Machinery Corporation, Paterson, N. J., a Corporation of New Jersey

Application January 22, 1931, Serial No. 510,583,
and in Denmark February 4, 1930

9 Claims. (Cl. 101—28)

This invention relates to stitch marking devices and is herein illustrated as embodied in a device for marking a guide line on a shoe upper blank.

5 For the purpose of ornamentation, many kinds of leather work and especially women's shoes are commonly decorated by fancy stitching or by rows of small perforations applied along lines having a predetermined configuration so as to 10 produce a fancy design. It has long been recognized that such ornamental designs can only be satisfactorily produced upon pieces of work by providing the work blanks with guide lines which can be followed by the operative but which will 15 be either inconspicuous or invisible in the completed work. For the production of a good grade of work it is important that the guide lines shall be accurately located upon the pieces of work and in the case of shoe upper blanks this means 20 that they must be differently located for every size of blank and reversed in position for rights and lefts. Various machines and devices have been provided for this work which, however, are frequently expensive and the dies or markers for 25 which can not readily be produced in a shoe factory.

Accordingly, an important object of the present invention is to provide a simple and inexpensive stitch marking device which will produce 30 a good grade of work with a minimum of skill on the part of the operative and which, if desired, may readily be manufactured by the shoemaker.

The illustrated device utilizes a slotted sheet 35 for supporting in position one or more metal strips with serrated edges and which are set on edge in the slots of the sheet to project both above and below the sheet so that pressure applied to the edges of the strips on one side of the sheet 40 will cause the other edges to be impressed in the work. This arrangement makes the device inexpensive, as will later be pointed out, and also facilitates the pressing of the various strips uniformly into the work. This novel arrangement 45 also makes the device reversible so that it is suitable for use on either a right or a left shoe. Preferably, and as shown, the device is shaped to conform to the outline of the part upon which it is to be used, thus facilitating the accurate 50 location of the device on the work.

Other features of the invention relate to a novel form of marking strip which can be produced cheaply to provide a strip which, as illustrated, has wedge-shaped edges which are 55 notched at regular intervals so as thereby to pro-

duce a dotted line upon the work, and the sides of which are roughened or corrugated to help in holding the strip in the device. These and other features of the invention are more fully discussed in the following specification taken in connection with the accompanying drawing in which—

Fig. 1 is a plan view of a marking device constructed in accordance with my invention;

Fig. 2 is a fragmentary section on a larger scale through said device and one of the marking strips;

Fig. 3 is a side elevation of the marking strip employed;

Fig. 4 is an enlarged perspective view of the strip; and

Fig. 5 is a view of a piece of work which has been marked by my device.

My marking device comprises a piece 10 of sheet material which is provided with a plurality of slots 12 which are substantially filled by means 75 of metal strips 14 held frictionally therein and exposed at top and bottom. Conveniently the piece 10 may be made of red fiber or of pattern board and shaped like the pattern which is employed in cutting out a shoe upper blank. This material is 80 relatively inexpensive and at the same time is sufficiently durable to withstand a considerable amount of usage without damage. It also is soft enough to be easily worked.

Patterns of this material are quickly and 85 inexpensively constructed by means of a machine (not shown) known as the pattern-grading machine which duplicates pieces by means of a pantographic construction and cuts the outline desired by a small reciprocating tool moved progressively along the work and forming a series of overlapping perforations. Shoe factories of substantial size are usually equipped with these machines and the same machine can be employed for both cutting out the pattern-shaped piece according to the desired outline and also for providing slots 12 in the piece to receive the marking strips 14. These slots are formed with the same facility that the outline of the piece is cut and only require that the operator of the grading 95 machine shall follow the design provided upon a master pattern. By means of adjustments provided on the grading machine the location of these slots may be automatically varied with pattern pieces of different sizes thus requiring a 100 minimum of skill and expense.

It will be understood that in the use of the device the pattern-shaped piece 10 is laid upon a piece of work 20 having the same outline with the edge of the piece 10 in register with the edge 110

of the work. Pressure is then applied by means of any suitable press which will be transmitted height-wise of the metal strips to force their lower edges into the work thereby to produce in dotted lines 22, 24 the design along which the shoe upper blank 20 is to be ornamented. This mode of operation, provided that the metal strips 14 are of uniform width, or height as they are located in the completed device, insures a uniformity of pressure upon the work to the end that the design will be perfectly reproduced thereon and so readily visible that the operator of a sewing machine or a perforating machine can follow the outline of the marks 22 and 24 with great ease. Quite obviously no strain is imparted to the sheet 10 and said sheet serves merely to support the strips 14 in upright position along the lines of the desired design. It also serves to locate the stitch marking device upon the work. Being light and easily handled, the marking operation can be carried out accurately with considerable speed and the same device employed for both rights and lefts.

While the exact form of the marking strip 14 may be varied within wide limits without departing from the invention, I have found that a strip of a construction to be described produces particularly good results and is easily manufactured. This strip, as shown in side elevation in Fig. 3 and enlarged perspective in Fig. 4, is a substantially flat brass strip the margins 26 of which are wedge shaped and slightly rounded at the edges so as not to cut the leather. The wedge-shaped edges of the strip are serrated by reason of a succession of notches 28 so as thereby to reduce the necessary pressure with which the device is applied to the work and to avoid damaging the leather by reason of a continuous crease. Preferably and as shown, the side faces of the strip are provided with a series of corrugations or slight depressions 30, thereby improving the frictional grip between the strip and the sheet 10.

Having described my invention, what I claim as new and desire to secure by Letters Patent of the United States is:

1. A marking device comprising a rigid sheet provided with one or more narrow slots following the configuration of the design to be marked, thin metal strips having serrated edges in said slots, the width of each strip being greater than the thickness of the sheet to the end that pressure applied to one edge will be transmitted directly through the strip to a piece of material placed in contact with the other edge and an impression made on the piece of work.

2. An unmounted reversible stitch marking device comprising a sheet of material supporting a marking strip which is curved to follow the configuration of the design to be marked and is exposed on opposite sides of the sheet of material, thereby providing reversed marking edges enabling the device to be placed either side up on a piece of work.

3. An unmounted reversible stitch marking device comprising a sheet of material provided with an integral marking member extending through said sheet of material and exposed on opposite sides thereof along a line forming the configuration of the design to be marked whereby one edge of the marking member may be applied to the work and pressure applied to the other edge to impress the design in the work.

4. A reversible stitch marking device comprising a sheet of material provided with a slot following the configuration of the design to be marked, and a marking blade held frictionally in said slot, the width of said blade being greater than the thickness of the slotted material.

5. A reversible stitch marking device comprising a pattern-shaped piece of material the outline of which corresponds to either a right- or left-hand shoe part depending upon its position upon the work, said pattern-shaped piece being provided with a slot following the configuration of the design to be marked, and a thin edged marking blade held frictionally in said slot, the width of said blade being greater than the thickness of the pattern-shaped piece.

6. A reversible stitch marking device comprising a piece of pattern board shaped like pieces of work to be marked and reversible for either right or left shoes, said pattern board being provided with a narrow slot following the configuration of a design to be marked on the shoe part, and a marking blade frictionally held in said slot following the configuration thereof, said blade being wider than the pattern board is thick and projecting above and below said board and being provided with exposed serrated edges, to the end that said marking device may be used either side up to impress a dotted line upon a piece of work.

7. A strip of metal for a marking device having its opposite edges wedge-shaped and provided with a series of notches.

8. A strip of metal for a marking device having a corrugated side and a notched edge.

9. A strip of metal for a marking device having a roughened side and a wedge-shaped edge provided with a series of notches.
